(57) **CLAIM**

The ornamental design for a clip structure for valuables, as shown and described.

DESCRIPTION

FIG. 1 is a side view of a first embodiment of the clip structure for valuables showing my new and ornamental design with the loop extended therefrom, the opposite side being a mirror image thereof;

FIG. 2 is a side view showing the loop of FIG. 1 being wrapped thereabout, the opposite side being a mirror image thereof;

FIG. 3 is a top plan view thereof;

FIG. 4 is a front-end view, the opposite end being a mirror image thereof;

FIG. 5 is a side view of a second embodiment of the clip structure for valuables having a superimposed pair of pocket-forming planar members with a loop extended therefrom, the opposite side being a mirror image thereof;

FIG. 6 is a side view showing the loop of FIG. 5 wrapped thereabout, the opposite side being a mirror image thereof;

FIG. 7 is a top plan view thereof; and,

FIG. 8 is a front-end view, the opposite end being a mirror image thereof.

The broken line showing of environment in the drawings is included for the purpose of illustrating only and forms no part of the claimed design.
